Primary Examiner — Thomas Johannes*Assistant Examiner* — Jasmine Mlinarcik(74) Attorney, Agent, or Firm — Shook, Hardy and Bacon L.L.P.(57) CLAIM

The ornamental design for a garment, as shown and described.

DESCRIPTION

FIG. 1 is a front perspective view of a garment showing my new design;

FIG. 2 is a front elevation view thereof;

FIG. 3 is a rear elevation view thereof;

FIG. 4 is a top plan view thereof;

FIG. 5 is a first side elevation view thereof; and,

FIG. 6 is a second side elevation view thereof.

The even-length broken lines shown in the drawings are directed to environment and form no part of the claimed design.
